[57] CLAIM

The ornamental design for a wastebasket, as shown and
described.

DESCRIPTION

FIG. 1 is a perspective view of a wastebasket showing
my new design;

FIG. 2 is a front elevational view thereof;
FIG. 3 is a left side elevational view thereof, the right
side view being a mirror image of that shown;

FIG. 4 is a rear elevational view thereof;

FIG. 5 is a bottom plan view thereof;

FIG. 6 is a top plan view thereof.
